BELT SANDER

Hjalmar T. Lundquist, Kennett Square, Pa.

Application October 30, 1943, Serial No. 508,322

8 Claims. (Cl. 51—135)

This invention relates to grinding machines, and more particularly to an endless belt type of sanding machine by means of which objects of variable shape can be rapidly and efficiently sanded or ground.

The object of the present invention is to provide an improved and simplified sanding machine of the endless belt type, having increased flexibility coupled with provisions for maintaining uniform abrasive pressure throughout the grinding surfaces.

The invention consists in the novel construction, arrangement and combinations of parts hereinafter more particularly described and claimed.

Two sheets of drawings accompany this specification as part thereof, in which like reference characters indicate like parts throughout.

Figure 1 is a front elevation of the improved device with the front frame cover removed.

Figure 2 is a vertical medial cross-section.

Figure 3 is a horizontal cross-section taken on line 3—3 of Figure 1.

Figure 4 is a horizontal cross-section taken on line 4—4 of Figure 1.

Figure 5 is a horizontal cross-section taken on line 5—5 of Figure 1.

Figure 6 is a horizontal cross-section taken on line 6—6 of Figure 1.

Figure 7 is a vertical cross-section through the belt supporting assembly.

Figure 8 is a fragmentary side elevation of the belt supporting assembly.

In accordance with the present invention, a back frame member 1 of substantially rectangular form is provided having a medial trough-like notch 2 formed in its upper edge and having a peripheral flange 3 upon which is adapted to seat a cover 4 having in its upper face a similar notch complementary to the notch 2, the two frame parts 1 and 4 constituting a housing for the grinding mechanism hereinafter described.

Mounted upon the back 1 are a plurality of stub shafts arranged in pairs, the uppermost pair of shafts 6—6 being horizontally spaced so that one of these shafts is positioned on either side of the medial notch 2. Below these stub shafts are positioned another pair of shafts 8—8. Upon the shafts 6—6 are rotatably mounted multiple sheave pulleys 7—7 arranged so that the sheaves are staggered, one with respect to the other, as illustrated in Figure 3, while on shafts 8—8 are rotatably mounted multiple sheave pulleys 9—9 staggered in the opposite direction as illustrated in Figure 4.

Below this assembly of freely rotatable pulleys are arranged a pair of multiple sheave pulleys 13 fixedly secured to shafts 12 journaled in back frame member 1 and suitably connected as by couplings 11—11, with motors or other driving means 10—10 mounted on the back of frame member 1.

An endless belt 17 is carried in the sheaves of the pulleys 7, 9 and 13 having the final reach 10 extending around a single sheave pulley 14 mounted upon a shaft 15 on the ends of which are suspended rotatably the weights 16—16 adapted to exert a uniform pressure upon the belt 17 and adjust itself angularly with respect to the front groove in pulley 13 and the rear groove of pulley 7.

The outer face of the belt 17 is provided with a suitable abrasive material and by the arrangement thus far described it will be apparent, by reference to Figure 1, that similar reaches of the belt 17 will cross each other medially of the notches 2 in the frame structure, providing a work-receiving trough 26 formed by angularly disposed stretches of the abrasive belt.

Supporting means for these trough-forming stretches of the abrasive belt is provided by a member 18 supported from the back 1 as by bolt 30, the member 18 being provided, as illustrated in Figure 7, with oppositely disposed cutaway portions

30 through which extend shafts 19 upon which are pivotally mounted arms 20 extending alternately from one side shaft 19 and the other to correspond with the reaches of the belt 17. Each of these arms 20 is provided near its free end with a planar face 22 adapted to contact and support a reach of the belt 17 adjacent the line of intersection of the portions of the belt constituting the work trough 26. The arms 20 on each shaft 19 are spaced by spacer rings 21, each provided with a radially disposed rod 24, the free end of which fits slidably in a hole 23 provided in the rear edge of the oppositely disposed arm 20.

Compression springs 25 surrounding rods 24 and bearing respectively against the spacer rings 21 and the rear face of the arms 20 operate to resiliently support each of the arms 20, thereby supporting the corresponding reach of the abrasive belt 17 by which structure it will be apparent that the work trough 26 is formed by a plurality

45 of angularly disposed reaches of the abrasive belt traveling in opposite directions, each reach of the belt resiliently supported by an arm 20 whereby objects of straight or irregular contour can be effectively sanded. It will also be observed that regardless of the shape of the object sanded, the

tension on the endless abrasive belt 17 will be uniform throughout at any given time.

Variations in the particular construction will readily suggest themselves to those skilled in the art but within the scope of the present invention, as claimed.

Having thus described my invention, I claim:

1. Sander comprising a frame having a plurality of stub shafts supported thereon, a plurality of multiple sheave pulleys mounted on said shafts, two of said pulleys arranged in spaced relationship to provide space between them for a work receiving trough, a single sheave pulley having a depending weight, and an endless belt having one face provided with an abrasive surface, said belt supported on said multiple sheave pulleys and carrying the weighted single sheave pulley, to form the intersecting walls of the work receiving trough said portions of the belt forming said trough walls all moving toward the line of intersection.

2. Sander comprising a housing including a back frame member, a plurality of stub shafts mounted on the back within the housing, a plurality of multiple sheave pulleys mounted on said shafts, two of said pulleys arranged in spaced relationship to provide space between them for a work-receiving trough, an endless belt having an abrasive-coated outer face supported on said pulleys to intersect to form the walls of the work-receiving trough with all reaches of the belt constituting said trough arranged to move toward the line of intersection, the housing and back frame member notched to conform with said work-receiving trough.

3. Sander comprising a frame, a plurality of pulleys mounted thereon including a driving pulley and a freely suspended weighted pulley and an endless belt positioned on said pulleys having its outer face provided with an abrasive surface, said pulleys arranged to direct said belt through a plurality of reaches constituting a work

trough having angularly disposed sides, the reaches of belt constituting each side of said trough traveling in the same direction and the freely suspended pulley being of a diameter to direct the belt from a pulley at one end of said trough to a pulley at the opposite end of said trough.

4. Sander comprising a frame, a plurality of pulleys mounted thereon, an endless belt positioned on said pulleys having its outer face provided with an abrasive surface, said pulleys including driving pulleys and a belt supported tightening pulley arranged to direct said belt into a plurality of reaches constituting a work trough having angularly disposed sides, all reaches constituting each side of said trough traveling in the same direction, and the reaches of both sides traveling in converging directions, the belt tightening pulley of a suitable diameter to direct the belt from a pulley groove at one end of said trough to the pulley groove at the opposite end of said trough.

5. Sander comprising a frame, a plurality of pulleys mounted thereon including a driving pulley and an endless belt having its outer face provided with an abrasive surface, said belt arranged on said pulleys and said pulleys so arranged as to present a plurality of reaches of said belt forming a work trough the sides of which converge, said sides each formed by reaches of said belt and all of said side forming reaches of said belt arranged to travel toward the bottom of the trough.

6. The device of claim 5 with means for maintaining said belt under uniform tension.

7. The device of claim 5 with means for supporting the trough forming reaches of the belt.

8. The device of claim 5 with independent means for resiliently supporting each of the trough forming reaches of the belt.

HJALMAR T. LUNDQUIST.
